UNITED STATES PATENT OFFICE.

HENRY W. GRIFFIN, OF NEW YORK, N. Y., ASSIGNOR TO THE UNION SWITCH AND SIGNAL COMPANY, OF SWISSVALE, PENNSYLVANIA, A CORPORATION OF PENNSYLVANIA.

RAILWAY SIGNALING SYSTEM.

No. 820,411.

Specification of Letters Patent.

Patented May 15, 1906.

Application filed January 18, 1905. Serial No. 241,546.

To all whom it may concern:

Be it known that I, HENRY W. GRIFFIN, a citizen of the United States, residing in the borough of Manhattan, city, county, and State of New York, have invented certain new and useful Improvements in Railway Signaling Systems, of which the following is a specification.

My invention relates to railway signaling systems.

I will describe a railway signaling system embodying my invention and a variation or modification of the signaling system also embodying my invention and then point out the novel features thereof in claims.

In the accompanying drawings, Figure 1 is a diagrammatical view illustrating a portion of a railway, a railway-signal, and applied thereto an arrangement of circuits constituting a signaling system embodying my invention. Figs. 2, 3, and 4 are views similar to Fig. 1, but showing different conditions of the parts and system illustrated in Fig. 1, due to the passage of a train along a railway. Fig. 5 is a view similar to Figs. 1 to 4, but showing a variation or modification of the signaling system therein illustrated. Fig. 6 is a view similar to Fig. 5, but showing a different condition of circuits. Fig. 7 illustrates a portion of a continuous signaling system in all respects like the signaling system illustrated in Figs. 1 to 4. Fig. 8 illustrates the signaling system of Fig. 7, but showing different conditions of the parts and system due to the presence of a train. Fig. 9 illustrates a variation of the signaling system illustrated in Figs. 1 to 4. Fig. 10 is a view similar to Fig. 7, but showing a different condition of the system and parts.

Similar characters of reference designate corresponding parts in all of the figures.

Railway-signaling as it is generally understood consists in the location of signaling devices at different points on a railway, which signaling devices are used to give indications or warnings to a driver of a train or car whether or no he can proceed with his train or car. A signaling device in one position or displaying one color gives one indication or warning and in another position or displaying another color gives another indication or warning. These signaling devices are provided or equipped with suitable mechanism

for operating them, and this mechanism may be automatic in its operation and automatically controlled; automatic in its operation and manually controlled, or manually operated.

Block-signaling as it is generally understood consists in the location of signaling devices at different and successive points along a railway whereby trains or cars traveling along the railway will be spaced apart, and thereby protected in their passage along the railway.

Automatic block-signaling as it is generally understood consists in the automatic operation and automatic control of the signaling devices. The automatic control is obtained through an arrangement of electrical circuits whereby a change of condition in one circuit produces or causes a change in condition of one or more other circuits. It is such an arrangement of circuits which is generally termed a "system." The different circuits in one condition affects certain apparatus comprised therein to have or permit of the signaling devices also comprised in the system being in one position of indication or caused to display one color, and the same circuits in another condition again affect the apparatus comprised therein to have or permit of the signaling devices being moved to another position of indication or caused to display another color.

By the term "system" as herein used and as contemplated by my invention I mean an arrangement or combination of electrical circuits so arranged that a change in condition of any one circuit in the arrangement or combination causes a change in condition of one or more other circuits, and thereby controls or effects the operation of apparatus that may be included in the system. Two changes in condition of a circuit which I herein employ are, first, the condition of being closed and, second, the condition of being open. There may be a third change in condition—to wit, that of being closed, but the current flowing therein being so weak or small as not to have any appreciable operative effect on the apparatus included in the circuit.

The railway-signals, which may conveniently be embodied or included in the system embodying my invention, comprise a signal device, an operating mechanism or apparatus

for moving the signal device from one position of indication to another position of indication, and a means or mechanism for at times and under certain conditions holding the signal device in the position to which it has been moved by the operating mechanism or apparatus. Preferably the operating mechanism is automatic in its operation. The signal device may be any which by its color or by its position relatively to its support gives indications of the service condition of the railway-track or section of railway-track which it governs. Ordinarily the signal device is in the form of a semaphore, which, as it is well known, comprises a blade and a counterweight, the latter also serving to carry colored glass, which is used in connection with a light. The blade is employed for indications during the day and the colored glass and light for indications at night or other times when the blade is not easily visible. This is well known and need not be described. As is usual, the semaphore (I will hereinafter use this term instead of signal device, though it should be understood that my invention is not limited to this particular form of signal device) is mounted on a post or other support in such manner that its counterweight always acts to move the blade to a horizontal position. This horizontal position is availed of as a position of indication and generally termed the "danger" or "stop" position of the semaphore. Usually operating mechanism or apparatus of some sort or nature is employed upon an expenditure of energy of some sort or nature to move the semaphore from its horizontal position to one or more inclined positions, depending upon whether the semaphore is to be used for two or three positions of indication. In the invention herein set forth the semaphore is used for two indications. Its horizontal position is availed of for one position of indication and its inclined position availed of as another position of indication. The horizontal position is termed the "danger" position of the semaphore, and in this position one color, generally red, is displayed. The inclined position is termed the "safety" position of the semaphore, and in this position another color is displayed, which may be white, green, or yellow. The color to be displayed in any of the positions of the semaphore may be any desired. The "holding means," as I shall hereinafter term them, generally comprise an electrically operated or actuated part, and only at such times that an electric current or an electric current of sufficient energy is present in the energizing winding or coil associated with such part is the holding means effective to retain the semaphore in its inclined position or safety position. When an electric current or an electric current of sufficient energy is not present in the energizing-winding, the

holding means is ineffective to perform its function, and the semaphore under the action of its counterweight assumes its horizontal or danger position.

The motive power for the mechanism or apparatus may be electricity or a fluid under pressure. An example of a railway-signal operated by electricity and embodying a holding device may be found in United States Patent No. 600,385, granted March 8, 1898, to V. K. Spicer, or in United States Patent No. 611,943, granted October 4, 1898, to J. G. Schreuder. An example of a railway-signal operated by a compressed fluid and embodying a holding device may be found in United States Patent No. 745,309, granted November 24, 1903, to J. P. Coleman. I have not herein specifically illustrated any form of automatic railway-signal, as my invention is applicable to any type of railway-signal comprising a holding means or which may have applied to it a holding device, which holding means acts at times to hold the semaphore or other signal device in any position to which it has been moved by the operating mechanism or apparatus.

The semaphores or other signal devices of the railway-signals included in the system should usually be in a horizontal or danger position of indication—that is to say, a train or car approaching a railway-signal will, if the conditions warrant, act to affect certain circuits to cause the operating mechanism or apparatus to move the semaphore thereof from its danger position to its safety position of indication, and the train or car after passing the railway-signal so operated again acts to affect the operating mechanism or apparatus, or more particularly the holding mechanism, to permit the semaphore to again return to its danger position under the influence of its counterweight. In other words, after a train or car passes a railway-signal which it has caused the semaphore thereof to be moved to safety position the train by its action renders the holding device inoperative to hold the semaphore in its safety position, so that the counterweight acts to return the blade to its danger position.

Referring now to Figs. 1 to 4 of the drawings, A designates a portion of a railway-track, the opposite lines of rails of which are electrically divided into sections by means of insulation *a*, placed at suitable points. The purpose of this is to make use of the rails of the railway in electrical circuits. The section of railway-track between two adjacent insulation-points is generally termed a "track-section." Each track-section (in Figs. 1 to 4 I have shown two, designated 1, 2, and parts of two others, designated 3 and 4) is provided at one end with a source of current-supply X, such source of supply being electrically connected with the rails of the

track-section and a relay or translating device R at its other end, which is also electrically connected with the rails of the track-section. So long as this circuit is complete current from the source of supply flows through the track-rails and relay, and the relay will, being energized, act through its armature *r* to control one or more circuits, as will herein-after be described. In this circuit, which is generally termed a "track-circuit," is interrupted, so that current does not flow through the relay, or the source of current is short-circuited or shunted—as, for example, by a pair of wheels and their axle of a train bridging the track-rails—the relay will be either wholly deenergized or deenergized to such an extent as to act through its armature *r* to again control the same circuits or still other circuits. In other words, the relay responding to the presence or absence of current in its energizing-coil acts through its armature to control a circuit or circuits. Therefore, leaving out accidental breaks of the continuity of the track-circuit when no train or part of it is in any track-section, the track-circuit thereof is complete and without short circuit or shunt, and the relay thereof attracts its armature to control one or more circuits. With a train or any part of it in the track-section it acts as a short circuit or shunt for the source of supply of the track-circuit thereof, and this practically deprives the relay of current. The relay becoming deenergized, its armature falls or is pulled away from the core of the energizing-coil and its front contact onto its back contact to again control one or more circuits or the same circuit or circuits which it controlled when attracted by the energizing-coil. Each block-section is provided at its entrance end with a railway-signal, which serves to protect the passage of train in and through its block-section. S designates one such railway-signal and S' another. The distance of railway between the signals S and S' is termed a "block-section," and, as here shown, only includes one track-section and track-circuits. However, each block-section may comprise a plurality of track-sections and also a plurality of track-circuits, any or all of which may control or affect the operation of its and other railway-signals. Each railway-signal comprises a semaphore or other signal device *s*, an operating mechanism comprising an electrically-operated part or device M, and a holding means also comprising an electrically-operated part or device H. The form of motor comprised in the operating mechanism is immaterial. Either form of operating mechanism of the patents herein referred to may be employed. Each has an electrically-operated part or device comprised in the operating mechanism, and the part so designated in the drawings may be considered that part. Each of the railway signal apparatus in the

patents referred to has a holding means, which serves to hold or retain at times the semaphore in its safety position only, and each of the holding means comprises an electrically-operated part or device which controls the effectiveness of the holding means. The part so designated in the drawings may be considered that part. The part M is included in an electrical circuit, which I herein term a "motive-power" circuit, and the part H is included in an electrical circuit, which I herein term a "holding-circuit." The holding and motive-power circuits are what may be termed "local" circuits—that is, they are usually local to the railway-signal, as is shown in the drawings, but may not be when other track-circuits also control the holding-circuit. These circuits may be supplied with current from the same or different sources, which sources of current may or may not be adjacent to the railway-signal. In the drawings I have shown these circuits as being supplied from a battery X'. The usual condition of the holding-circuit is closed. The energizing-coil included in the part H being of high resistance retards battery consumption. The usual condition of the motive-power circuit is disabled or open, it being only energized or closed when it is desired to move the semaphore *s* from its danger position to its safety position. The holding-circuit is controlled from the relay R of a track-circuit of the block-section which the railway-signal guards or protects. The motive-power circuit is controlled, first, by a relay C, included in what I herein term a "clearing-circuit;" second, by the relay in the track-circuit of the block-section which the railway-signal guards or protects, and, third, by one or more circuit-controllers mechanically operated by the railway-signal. I'll designate two such circuit-controllers, which may be of any desired construction and incorporated and operated by the railway-signal in any desired manner. For example, the circuit-controllers I and I' may be incorporated and operated in the same manner as are the circuit-controllers of United States Patent No. 600,385, hereinbefore referred to, except as hereinafter provided. The clearing-circuit is controlled by a relay or relays of one or more preceding track-circuits.

Figs. 1 to 4 illustrate the necessary circuits for operating one railway-signal. Every other railway-signal may be provided or equipped with the same arrangement of or system of circuits. Fig. 1 illustrates the usual condition of the circuits and parts. The track-circuits of track-sections 1 and 2 are closed. The clearing-circuit is open, which, starting from the battery X', is wire 5, armature *r* and its back contact, wire 6, relay C, wire 7, and battery X'. The holding-circuit of the railway-signal is closed, which, starting from the battery X', is wire 8, armature *r* and

its front contact, wire 9, circuit-controller I, wires 10 and 18, coil of holding device II, wire 11 to battery. The motive-power circuit is open, which, starting from the battery 5 X' , is wire 8, armature r and its front contact, wires 9 and 19, circuit-controller I', wires 20 21, electrical device M, wires 22 23, front contact and armature c of relay C, (when this circuit is open,) and wires 24 and 11 to battery. In Fig. 2 a train T has just entered the track-section 1. The first pair of wheels and their axle of the train in bridging the rails of track-section 1 act as a short circuit for the battery X of that track-circuit, and 10 the relay R becoming deenergized its armature moves away from its front contact onto its back contact, thus completing or closing the clearing-circuit. The relay C is then energized by current from the battery X^2 and 15 attracts its armatures $c' c'$ to close the motive-power circuit, which, as stated, included the electrically-operated device M. The operating mechanism of the railway-signal then acts to move the semaphore s from its danger position. The parts and circuits will 20 then be in the condition illustrated in Fig. 3 and will remain in this condition during the passage of the train or car through track-section 1 and until the first pair of wheels and 25 axle enter track-section 2. The moving of the semaphore to its safety position is an indication that the block-section 2, protected or guarded by the railway-signal S, is clear of trains or cars and in serviceable condition. 30 Should any train or car or any part of it be on the rails of track-section 2, it acts as a short circuit for the battery X of the track-circuit of that section, and the relay R thereof being deenergized opens the holding-circuit and the 35 motive-power circuit, so that the semaphore cannot be moved to its safety position. This condition is illustrated in Fig. 4, assuming the train T not to be the train T in Fig. 3. Fig. 4 also indicates the conditions of the 40 circuits after the train T has entered track-section 2. The wheels and axles upon entering track-section 2 act as a short circuit for the battery X , comprised in the track-circuit of track-section 2, and the relay R of that track- 45 circuit becoming deenergized its armature moves to open the holding-circuit and permits the semaphore under the influence of its counterweight returning to its danger position. So long as the train or car or any part 50 of it remains in the track-section 2 the semaphore remains in its danger position and cannot be moved to its safety position by the action of a train entering track-section 1. After the train or car moves completely out of 55 track-section 2 the circuits and parts assume the condition shown in Fig. 1, in which condition the railway-signal is ready to be again operated by a train or car entering track-section 1.

60 The relay C, in fact, has only one armature;

but it is made to engage two front contacts. This arrangement is diagrammatically illustrated by two armatures $c' c'$ engaging contacts. This is true of every other relay illustrated as having more than one armature. 70

In connection with the holding means this device, notwithstanding the fact that the circuit through the energizing-coil included in such device is usually closed irrespective of the position of the indication of the semaphore, acts only so long as its circuit is closed and sufficient current is flowing therein to retain the semaphore in its safety position after the semaphore has been moved to that position. This will be readily understood 80 upon reference to either of the Letters Patent herein referred to.

The circuit-controller I is so constructed and arranged that it closes a circuit—to wit, battery X' , wires 8 9 12 13 14, armature c' 85 and its front contact, wires 15 16 17 18, part H and wire 11 before it breaks the circuit—battery X' , wires 8 9 10 18, part H, and wires 11 to battery X' . This circuit-controller is so constructed this way and the transfer-circuit 90 12 13 14, &c., provided in order that the semaphore s would be put to "danger" in case a train or car did not pass it and backed out of track-section 1.

Referring now to Figs. 5 and 6, substantially the same arrangement or system of circuits is employed as illustrated in Figs. 1 to 4. The difference is that when the clearing-relay C is deenergized its armature moving onto a back contact closes a shunt-circuit of 100 low resistance around the part H—to wit, from battery X' , wires 11 24, armature c' , wire 25 and resistance R^3 , wire 26, circuit-controller I, wire 9, armature r , and wire 8 to battery. This circuit is used only when a 105 train or car entering track-section 1 does not proceed through it and pass the signal S, but, on the contrary, moves out of the track-section 1 at the end in which it entered or onto a branch track. As this occurs it is necessary 110 to again return the semaphore to its danger position. This is accomplished through the relay R of track-section 1 opening the clearing-circuit as the train or car passes out of the track-section, and the clearing-circuit being 115 opened the clearing-relay C drops its armature onto its back contact, thereby closing the shunt-circuit—to wit, from battery X' , wires 11 24, armature c' , wire 25, and resistance R^3 , wire 26, circuit-controller I, wire 9, armature r , and wire 8 to battery. Just before 120 this operation the car or train leaving block-section 1 without entering block-section 2 the circuits and parts will be in the condition illustrated in Fig. 6.

In Figs. 7 and 8 a portion of what may be termed a "continuous" system of signaling is illustrated—that is, a system of signaling embodying my invention applied to a number of succeeding block-sections. The system 125 130

illustrated in these two figures is in all respects like that illustrated in Figs. 1 to 4. Fig. 7 illustrates what may be termed the "normal" or "usual" condition of the circuits and parts, and Fig. 8 the condition of circuits and parts when a train is in any one block-section.

It will be understood, of course, that in other systems of railway-signaling—to wit, "home" and "distant," "overlap," &c., or variations of these other systems—modifications will necessarily have to be made; but these will be obvious to any one skilled in the art. For example, a railway-signal may be caused to operate to move its semaphore or signal device from its danger position to its safety position through the action of a train on the second or third preceding track-section and maintained in its clear position until the car or train reaches or passes the railway-signal, after which the semaphore is returned to its danger position by its counterweight and maintained in its danger position through the action of the train passing through any number of succeeding track-sections. This is merely a matter of arrangement of what I have herein termed the "clearing-circuit," which is entirely distinct from the track-circuits of the track-sections and from what I have herein termed the "holding" and "motive-power" circuits. My invention may therefore be said to comprise closed track-circuits for controlling clearing-circuits, the latter in turn controlling motive-power circuits only, and holding-circuits, which are controlled, with their component motive-power circuits, by one or more other track-circuits.

In Figs. 9 and 10 I have illustrated a variation of the signaling system illustrated in Figs. 1 to 6. The system shown in Figs. 9 and 10 is what is technically known in the art as "home" and "distant" signaling, a home and distant signal being located on the same post at the entrance end of each block-section. The operating mechanism for the semaphores or signaling devices on each post may conveniently be the same as that illustrated in United States Patent No. 611,943, hereinbefore referred to. In this patent the two semaphores (indicated in these figures by s and s') are operated by a mechanism embodying a single electric motor, (indicated in these figures by M .) If desired, the semaphores s s' may be located on separate posts and each provided with its own operating mechanism, each of which would comprise an electrically-operated device M and a holding device H or D . Also in the system shown in Figs. 9 and 10 I employ what is known as a "polarized" relay R' for each track-circuit—that is, a relay which is provided with two armatures—one of which, r' , is a neutral armature and is attracted to the core of the coil or coils of the relay irrespective of the di-

rection of current through the coils, and the other of which, r^2 , is polarized and is attracted by current flowing through the coils in one direction only—that is, in a direction to close a circuit or circuits. The reversal of the current is obtained by means of what is technically known in the art as a "pole-changing" device P , which is preferably mechanically connected with a semaphore. These devices are well known in the art, and their use in this invention is the same as heretofore in signaling systems wherein the semaphores of the railway-signals are usually in their safety position of indication instead of in their danger position, as in this invention.

Referring now more particularly to Figs. 9 and 10, the railway is divided into block-sections 1, 2, 3, 4, and 5 in the usual manner. As shown each block-section comprises only one track-section. Each block-section is provided at its exit end with a source of current—to wit, a battery X —which is electrically connected with the rails of the block-section through a pole-changing device P . At the entrance end of the block-section is a polarized relay R' , which is also electrically connected with the track-rails of the block-section. The neutral armature r' of each polarized armature controls the motive-power circuit of the operating mechanism for the railway-signal for its block-section, the holding-circuit for the home semaphore s thereof, and the clearing-circuit for the home signal or two home signals succeeding any given block-section. The neutral armature r' also, in connection with the polarized armature r^2 , controls the holding-circuit for the distant semaphore s' , located beneath the home semaphore s at that point. Each holding-circuit for a home signal may be traced as follows: Starting from a battery X^1 , it is wires 30 70 71, armature r' of a track-relay, wires 72 73, circuit-controller I^1 , wires 74 75, holding device H , and wires 76 41 back to battery. When a home signal is moved to safety position, the circuit-controller I^1 is moved to close a transfer-circuit, which, starting from the circuit-controller I^1 , is wires 77 78, armature c' of clearing-relay C , (which will of necessity be energized before the home signal is moved from "danger" to "safety,") and wire 79 to wire 75. This is the same as described in connection with Figs. 1 to 4 and is for the same purpose. Each holding-circuit for a distant signal may be traced as follows: Starting from a battery X^2 , it is wires 70 71, armature r' , wires 72 73 80, armature r^2 , wires 81 82 83, circuit-controller I^2 , which is closed when the home signal above a distant signal is moved to "safety" from "danger," wires 84 85, holding device D , and wires 86 41, back to battery. The motive-power circuit for moving a home signal from "danger" to "safety" may be traced as follows: battery X^2 , wires 130

30 70 71, armature r^2 , wires 72 87, circuit-controller I', wire 88, part M, wires 89 90, armature c of a clearing-relay, and wires 91 41 to battery. The motive-power circuit for moving a distant signal from its horizontal to an inclined position may be traced as follows: battery X^2 , wires 30 70 71, armature r' , wires 72 73 80, armature r^2 , wires 81 82 92, circuit-controllers I and I', (I' being moved to point 93 when home signal is moved,) wire 88, part M, wires 89 90, armature c of a clearing-relay, and wires 91 41 to battery. A clearing-circuit for the home signal for the second block-section in advance of any particular block-section—to wit, the home signal for block-section 4, which is two blocks in advance of block-section 2—may be traced as follows: battery X^2 at block-section 2, wires 30 31 32, armature r' of relay R' of block-section 2, wires 33 34 35 36 37, clearing-relay of block-section 4, wires 38, 41, 39, 40, 102, and 41, back to battery X^2 . A clearing-circuit for the home signal for the next block-section in advance of block-section 2—to wit, block-section 3—may be traced as follows: battery X^2 at block-section 2, wires 30 31 42, armature r' of relay R' of block-section 2, wires 43 44 45 46, clearing-relay C of block-section 3, wires 47, 41, 103, 40, 102, and 41, back to battery. The wire 40 may be termed a "common" wire. The clearing-circuit for the home signal two block-sections in advance of block-section 3, for example, will be a battery X^2 , adjacent the block-section 3, wires 30 31 32, armature r' of track-relay R' of block-section 3, wires 33 34 35 36 37, clearing-relay C of block-section 5, wires 38, 41, 39, 40, 103, and 41, back to battery. The clearing-circuit for the home signal of the block-section next in advance of block-section 3—to wit, 4—will be battery X^2 , adjacent the block-section 3, wires 30 31 42, armature r' of track-relay R' of block-section 3, wires 43 35 36 37, clearing-relay C of block-section 4, wires 38, 41, 39, 40, 103, and 41, back to battery X^2 . It will be seen that several wires are common to different clearing-circuits. This is true of certain holding and motive-power circuits. This plan is adopted for cheapness in installation. Of course each circuit may be entirely complete in itself—that is, all wire in that circuit will be used only for that circuit and no others. The plan followed in the drawings and as described is thought to be the simplest and as affording the best method of illustrating and describing the invention.

As is well known, in the system illustrated in Figs. 9 and 10 a distant signal is located some distance in advance of its home signal, generally at a distance equal to the distance between two adjacent home signals. For example, the semaphore s' located at the entrance end of block-section 1, beneath the home semaphore s , is the distant semaphore

for the home semaphore s located at the entrance end of block-section 2, and similarly the semaphore s' located at the entrance end of the block-section 2 is the distant semaphore for the home semaphore s located at the entrance end of track-section 3. The home semaphores s control the passage of trains through the block-section at which they are located, while the distant semaphores act to serve as an indicator for their home signals. It will therefore be seen that the control of a distant signal should be affected by its home signal. This control of the distant signal by its home signal is effected by a reversal of the direction of flow of current in a track-circuit, the desired reversal being obtained by a pole-changer P, which is preferably mechanically connected with a home signal. For example, a movement of the home signal s at the entrance end of block-section 2 from its danger position to its safety position operates the pole-changing device P, provided in the track-circuit for block-section 1, which in turn reverse the direction of flow of current from the battery X through the track-rails and relay R for that track-circuit to cause a movement of its polarized armature r' , and thereby cause the holding-circuit for the distant signal located at the entrance end of block-section 1 to be closed. Also in this system a circuit-controller operated by the home signal directly above a distant signal is included in the holding-circuit of a distant signal. This is due to the fact that a distant signal should never be in its safety position unless its home signal is in the safety position.

In the application of my invention to home and distant system of signaling, aside from the changes in the holding-circuits due to the arrangement of two semaphores s and s' being operated from a common mechanism and the additions of the necessary apparatus to control a distant signal by its home signal, the only change over the system shown in Figs. 1 to 6 is to extend the clearing-circuit to include, preferably, the clearing-relays associated with two succeeding block-sections. For example, the clearing-circuit for block-section 2 includes the clearing-relays C, associated with the succeeding track-sections 3 4. This is desirable in that a train approaching any signaling-point will be enabled to obtain information of the service condition of the two next block-sections in advance of the block-section through which it is passing. For example, Fig. 9 illustrates what may be termed the "normal" or "usual" condition of the circuits and parts, and assuming that a train T is in block-section 2, as the train T first entered block-section 2 it short-circuited the battery X of the track-circuit for that block-section from the relay R, which being deenergized dropped its neutral armature r' to close a clearing-circuit which includes the

- clearing-relays C of the track-sections 3 and 4. (See Fig. 10.) These relays becoming energized close the motive-power circuits which they control, and thus cause the mechanism 5 for the home semaphores s, located at the entrance ends of track-sections 3 and 4, to operate and move them from their danger positions to their safety positions. As these semaphores reach their safety position and are 10 retained in this position they operate the pole-changing devices connected with them to control the mechanisms connected with their distant semaphores and have them operate to move the distant semaphores from their danger 15 positions to their safety position. This is well known and need not be described. Of course the distant semaphore s' (located at the entrance end of block-section 2) for the home signal s located at the entrance end of 20 track-section 3 will not be moved to its safety position, as the wheels and axles of the train or car act as a short circuit for the battery X for the track-circuit of that track-section and the relay becoming deenergized drops its neutral 25 armature, so that the holding-circuits for the home and distant semaphores are opened, as well as the motive-power circuit. As the train or car proceeds through the track-sections it successively acts as a short circuit for 30 the source of current provided for the track-circuits, thus depriving the relays of current, and they becoming deenergized open the holding and motive-power circuits of the semaphores which they control.
- 35 It will be understood, of course, that the presence of a train or car in any track-section will prevent the semaphore or semaphores guarding that track-section from being moved from their danger positions to 40 their safety positions, notwithstanding the fact that the clearing-circuit is closed by the entrance of a train or car into a track-section.
- Having thus described my invention, what I claim is—
- 45 1. In combination with a railway-signal comprising a signal device constructed to usually give a danger indication, an operating mechanism for moving it from danger indication to safety indication, means for at 50 times holding it in its safety indication, and an electric circuit for the holding means usually closed; of a clearing-circuit usually open and closed by the action of a train on a track-circuit, a motive-power circuit usually open 55 and closed by and upon the closure of said clearing-circuit, and another track-circuit for controlling the motive-power circuit and the electric circuit of the holding means.
2. The combination with an automatically- 60 operating railway-signal comprising a signal device usually indicating danger, and a holding means for at times retaining the signal device in its safety position when moved to safety, of a system for controlling said railway-signal comprising a plurality of track- 65
- circuits, a clearing-circuit usually open and closed by the action of a train on one of said track-circuits whereby the signal device is permitted to be moved, from its danger position to its safety position and there retained 70 by said holding device, and a holding-circuit which is usually closed and is opened by the action of a train on another of said track-circuits.
3. A railway signaling system for railway- 75 signals comprising a signal device usually indicating danger, automatically - operating mechanism for moving from danger to safety and other automatic means for at times retaining it in its safety position, which comprises a plurality of closed track-circuits, a clearing-circuit controlled by one of said track-circuits, a motive-power circuit usually open and closed by said clearing-circuit whereby the signal device is moved to safety, 80 and a holding-circuit usually closed and opened by the action of a train on another of said track-circuits whereby the signal is permitted to move to danger from safety. 85
4. The combination with a railway-signal 90 comprising a signal device usually indicating danger, an automatically-operating mechanism the supply of motive power to which is electrically controlled, a holding means comprising an electrically-operated device for at times retaining the signal device in its safety position and a circuit including said electrically-operated device which is usually closed and is opened by the action of a train to release the signal device from its safety position 95 whereby it may return to its danger position; of a system for controlling the operation of said mechanism to move the signal device from danger to safety comprising a closed track-circuit, a clearing-circuit usually open and closed by said track-circuit through the operation of a train on said closed track-circuit, and a motive-power circuit usually open and closed by said clearing-circuit upon the closure of said clearing-circuit. 100
5. The combination with a railway-signal 105 comprising a signal device usually indicating danger, an automatically-operating mechanism the supply of motive power to which is electrically controlled, and a holding means comprising an electrical device for at times retaining the signal device in its safety position when moved to safety; of a system for automatically controlling the positions of said signal device comprising a plurality of closed track-circuits; a clearing-circuit usually open and closed by the action of a train on one of the track-circuits; a motive-power circuit for controlling the motive power to the operating mechanism usually opened and closed by the closing of the clearing-circuit, whereupon the operating mechanism will move the signal device from danger to safety; and a circuit including the electrically-operated device of the holding means which is 110
- 120
- 125
- 130

usually closed and which is opened by the action of a train on another of said track-circuits.

6. In combination with a railway-signal comprising a signal device constructed to usually give a danger indication, an operating mechanism for moving it from danger indication to safety indication, means for at times holding it in its safety indication, and an electric circuit for the holding means usually closed; of a clearing-circuit affected by the action of a train on a track-circuit, a motive-power circuit usually disabled and energized by a change in the clearing-circuit, and another track-circuit for controlling the motive-power circuit and the holding means.
7. In combination with a railway-signal

comprising a signal device constructed to usually give a danger indication, an operating mechanism for moving it from danger indication to safety indication, means for at times holding it in its safety indication, and an electric circuit for the holding means usually closed; a motive-power circuit usually disabled and energized by the action of a train on a track-circuit, and another track-circuit for controlling the motive-power circuit and the circuit of the holding means.

In testimony whereof I have signed my name to this specification in the presence of two subscribed witnesses.
